UNITED STATES PATENT OFFICE.

FRANK W. RIESENBERG AND JOHN E. O'HEARNE, OF OMAHA, NEBRASKA.

AUTOMATIC BELL-RINGER.

SPECIFICATION forming part of Letters Patent No. 411,129, dated September 17, 1889.

Application filed April 16, 1889. Serial No. 307,484. (No model.)

To all whom it may concern.

Be it known that we, FRANK W. RIESENBERG and JOHN E. O'HEARNE, citizens of the United States of America, residing at Omaha, 5 in the county of Douglas and State of Nebraska, have invented certain new and useful Improvements in Automatic Bell-Ringers, of which the following is a specification, reference being had therein to the accompanying 10 drawings.

The device is intended to be operated by compressed air or steam. The drawings show it in its application to the bell of a locomotive-engine; but it is applicable to all oscillating bells. The ringing of the bell of a locomotive is used as a signal to denote the starting of the engine. It is also rung when approaching and passing over all road and street crossings to warn the drivers of vehicles and 15 pedestrians of the approach of the train. The most usual way to operate the bell has been to secure a crank-arm to the bell-shaft and to carry a cord from said arm back to the cab, when by pulling the cord the bell can be 20 rung, it being part of the duty of the fireman to ring the bell. On locomotives used for switching and making up trains and upon those used to pull suburban passenger-trains, where the service is constantly within the 25 limits of a city or town, it becomes necessary to ring the bell almost constantly, to do which and attend to the other requirements of his work is a great hardship to the fireman, and often impossible. To obviate this numerous 30 devices have been invented to ring the bell, it only being necessary to start and stop the same at will; but many have failed to give satisfaction. To accomplish the desired results and still produce a machine simple in 35 construction and inexpensive has been the 40 object of our invention.

In the drawings, Figures 1 and 2 are elevations of the bell-frame and bell with the bell-ringer constructed in accordance with our invention. Figs. 3 and 4 are sectional elevations of the ringer detached. Fig. 5 is a plan of the same. Figs. 6 and 7 show the trunnion in side view and transverse section. Figs. 8 and 9 show the valve in side view and transverse section. Figs. 10 and 11 show the valve-rod in front and side view. Figs. 12 and 13

show the valve-disk in front and side view. Figs. 14 and 15 show the valve rod and disk in their relative positions to one another.

In conformity with the general locomotive 55 practice the bell-frame A, which is secured to the boiler of the locomotive, receives the shafts a and a' , which are fastened to the yoke a^2 , the bell a^3 being bolted to the yoke a^2 . The crank-arm a^7 is secured to the shaft 60 a' , and from it to the cab is carried the cord used by the fireman to handle the bell. To attach the bell-ringer to the bell-frame, at a^4 is screwed the trunnion B, having the cylindrical chamber b and the hole b' at one end 65 and ports b^2 and b^3 cut into the walls of said chamber. Over the trunnion B is placed the cylinder C, while into the chamber b the hollow wing-valve D, Figs. 8 and 9, is placed. The valve and cylinder are then held in 70 place by screwing the nut b^4 on the end of trunnion B. The opening e in the valve-rod E is now passed over projecting end d of the valve D, while at the same time the end e' is inserted into the cylinder through an 75 opening in the cylinder-head c . The valve-disk F is next passed over the end d of the valve D, the pins f and f' projecting from the face of the disk coming on either side of the rod E. The disk is then made stationary to the valve by the pin f^2 , or in other suitable manner. Within the cylinder 80 C is the piston G, having the piston-rod g . The rod g is inserted through a hole in the crank-pin a^5 of the crank-arm a^6 , which is 85 keyed or riveted to the shaft a . The pipe H, screwed into the hole b' in the trunnion, conveys the air or steam from the boiler or air-pump to the bell-ringer.

Figs. 1, 2, 3, and 4 show the bell and bell-ringer in their normal position.

Having made all connections, to ring the bell the operator pulls the cord I, and by means of the arm a^7 partially revolves the shaft a' , the bell-yoke a^2 , the bell a^3 , and the 95 shaft a . The crank-pin a^5 of the arm a^6 , moving in a segmental path, acts upon the piston-rod g and oscillates the cylinder C upon the trunnion B until the ports c' in the cylinder match the ports b^2 in the trunnion, Fig. 4. 100 When the air or steam from the orifice b , which is fed by the pipe H, is admitted into

the cylinder C and under the piston G, it forces it and its rod *g* upward. The shoulder *g'* on the rod *g*, being in contact with the crank-pin *a⁵*, further oscillates the bell and causes it to ring. As the cylinder is oscillated it carries with it the rod E, which in its movement comes in contact with the pin *f*, Fig. 14, and turns the valve D within the trunnion B, so that the wing *d'* of said valve 5 closes the port *b³* and cuts off the air or steam supply to the cylinder, the piston being forced from this point to the end of its stroke by expansion. When the piston is near the end of its upward movement, it strikes and 10 lifts with it the rod E. As the rod E is lifted its angular face *e²* comes in contact with the pin *f'* and still further revolves the valve D. The ports *d²* in the valve now match the ports *b³* and *c'*, forming a free outlet from 15 the cylinder through the ports *c' b³ d²* and through the passages *d³* in the valve D, and out into the atmosphere, or with suitable connections into the smoke-box of the locomotive. The piston on being released of its 20 pressure is forced down by the gravitation of the bell. The valve-rod E also drops back of its own weight, not affecting the valve D, which is held stationary by the pressure upon it until again operated upon by the valve-rod E, thus giving ample time for release of 25 pressure. The momentum of the bell carries it backward and oscillates the cylinder upon its trunnion (in the opposite direction to that heretofore described) sufficient to bring the port *c'* in line with the port *b²*, when 30 the air or steam again enters the cylinder and the above-described proceeding is repeated, and will continue to be as long as it is desired to keep the bell in motion. To 35 stop the bell, the operator takes hold of the cord and brings the bell to its vertical position. The valve will then be in the position shown by Fig. 4, and will remain thus until again started. The crank-pin *a⁵* is made to 40 turn in the arm *a⁶*, and is free to move upon the smaller part *g²* of the piston-rod *g*.

In case too great a pressure is exerted upon the piston the momentum of the bell will cause the pin *a⁵* to slide upward on the piston-rod until met by the elastic resistance of the spring K, compressed against the nut L. By this arrangement serious jars are avoided 45 and the most natural vibrations of the bell are permitted.

As has been explained, the bell is handled solely by means of the ordinary bell-cord, and

requires no attention but to pull the cord to start it and to hold it for an instant to stop it.

Having now fully described the invention, what we claim as new, and desire to secure 60 by Letters Patent, is—

1. An oscillating cylinder, in combination with a hollow trunnion having two series of ports *b²*, and a valve within the trunnion, and a bell-supporting frame carrying said trunnion with a bell, substantially as and for the 65 purpose described.

2. The trunnion B, having longitudinal chamber *b*, provided with the opening *b'* and ports *b²* and *b³*, in combination with cylinder 70 C, and the valve D, having ports *d²* and the central passage *d³*, substantially as and for the purpose described.

3. The combination of the oscillating cylinder C, the trunnion B, having ports *b²*, the 75 valve D, having ports and a central passage, and the nut *b'* upon the end of said trunnion, substantially as and for the purpose described.

4. The combination of the oscillating cylinder C, the piston G, piston-rod *g*, and nut L, with the spring K upon said piston-rod, the pin *a⁵*, perforated to receive the piston-rod, the crank-arm *a⁶*, shafts *a* and *a'*, bell-yoke, and bell, substantially as and for the 85 purpose described.

5. The combination of the piston G, the cylinder and its perforated cover *c*, and the bent valve-rod E, entering the perforated cover, with the valve D, the disk F, and pins 90 *f* and *f'* upon said disk, substantially as and for the purpose described.

6. The combination of a bell-supporting frame, the trunnion B, the cylinder C, mounted upon said trunnion, the tubular valve D, 95 the valve-rod E, the valve-disk F, having pins *f f'*, and the piston G, adapted to lift the valve-rod, substantially as and for the purpose described.

7. The combination of a bell, a bell-supporting frame, the hollow trunnion B, the oscillating cylinder C, valve D, valve-rod E, valve-disk F, piston G, and rod *g*, with the crank-pin *a⁵* and crank-arm *a⁶*, substantially 100 as and for the purpose described.

In testimony whereof we affix our signatures in presence of two witnesses.

FRANK W. RIESENBERG.
JOHN E. O'HEARNE.
